Attorney

UNITED STATES PATENT OFFICE.

DAVID CONOVER, OF MOUNT VERNON, INDIANA.

CHURN.

SPECIFICATION forming part of Letters Patent No. 340,767, dated April 27, 1886.

Application filed December 4, 1885. Serial No. 184,656. (No model.)

To all whom it may concern:

Be it known that I, DAVID CONOVER, a citizen of the United States, residing at Mount Vernon, in the county of Posey and State of Indiana, have invented certain new and useful Improvements in Churns, of which the following is a specification, reference being had to the accompanying drawings.

This invention relates to improvements in churns, and is an improvement upon the churn upon which Letters Patent were granted me, No. 325,238, September 1, 1885, and has for its objects, first, to hold the body of the churn more firmly in the frame which supports it and the driving-crank; secondly, to prevent the lid from turning in the body of the churn while the operation of churning is in progress; thirdly, to enable the operator to examine the contents of the churn while in motion. These objects are attained by the mechanism illustrated in the accompanying drawings, forming part of this specification, in which—

Figure 1 is an elevation. Fig. 2 is a plan of the top of the churn with the operating mechanism removed. Fig. 3 is a sectional view. Fig. 4 is an enlarged view of the top of the churn, and shows (where a portion of the pieces forming the cover are broken away) 30 the position of the lugs L.

The letter A indicates the stand or frame upon which the churn is placed, which is provided with short legs a, preferably three in number, as this gives greater steadiness where 35 the floor or ground upon which the churn is placed happens to be uneven. Secured to the stand A is a vertical piece of wood, A', provided with a brace, A'', whereby greater steadiness between the stand A and vertical piece 40 A' is secured.

The vertical piece A' has an opening near the top for the passage of one end of a hollow casting, B, having a flange, b, provided with suitable bolt-holes and bolts, whereby the casting B may be firmly secured to the upright A'. This casting forms the bearing of the shaft c of spur-wheel C. The said shaft is provided with crank and handle D, by means of which rotary motion is given to the spur-wheel C, 45 thence to the pinion E and spur-wheels F G, as well as to their respective dashers H I, the

upper extremities of which are provided with shafts H' I', having bearings in the raised portion K of the lid, formed of two pieces, J J', which are provided with hooks i and staples 55 i', whereby they are secured to each other and maintained in their proper positions.

Secured to each side of the churn-body are lugs L, made, preferably, of thin sheet metal, which enter the space between the parts J J', 60 forming the lid of the churn. These lugs L are intended to maintain the body of the churn and the lid in their exact relative positions by preventing the one from turning upon the other, and if made of thin sheet metal they 65 occupy but little room, and therefore do not necessitate cutting away any portion of the pieces J J'. To the part of the lid J' is secured by means of hinges k a piece, K', thereby forming a door, which may be lifted by the operator 70 while churning for the purpose of observing the progress of the work.

Near the top of the churn-body is attached to the upright A' a crescent-shaped piece of wood or metal, M, having a small central 75 slot or opening, m, to receive the lug n on the outside of the churn-body, whereby the churn-body is prevented from turning upon its axis during the operation of churning.

A leather band or strap, R, is passed around 80 the churn-body near the top, and around the upright A'. This is intended to prevent the churn from slipping off the stand A, and to hold the whole together while churning, which may be quickly removed and adjusted, as cir- 85 cumstances require.

The dashers are of wood, and have a number of perforations, h. At the bottom they have pins P, which enter small metal thimbles o, secured to the bottom of the churn-body. 90

It will be observed from the foregoing that when the handle D is turned a revolving motion in opposite directions will be imparted to the dashers H I, and cause a great agitation to the contents of the churn, so that the operation 95 of making butter is very rapidly performed.

Having described my invention, what I desire to secure by Letters Patent and claim is—

1. In combination with the body of the churn, having lugs L, a cover consisting of two 100 pieces, J J', and a raised portion, K, the said parts J J' provided with hooks i and staples

i', and a hinged door, *K'*, as described, and for the purposes set forth.

2. In combination with the vertical piece *A'*, the crescent-shaped piece *M*, having slot *m*, the strap *R*, and the churn-body having a lug, *n*, as described, and for the purposes set forth.

In testimony whereof I affix my signature in the presence of two witnesses.

DAVID CONOVER.
